UNITED STATES PATENT OFFICE.

HERBERT I. FINCH, OF ST. LOUIS, MISSOURI, ASSIGNOR TO THE EMERSON ELECTRIC MANUFACTURING COMPANY, OF ST. LOUIS, MISSOURI, A CORPORATION OF MISSOURI.

REVOLVING VENTILATING-FAN.

1,267,752.

Specification of Letters Patent. Patented May 28, 1918.

Application filed July 13, 1916. Serial No. 109,146.

To all whom it may concern:

Be it known that I, HERBERT I. FINCH, a citizen of the United States, residing at the city of St. Louis, State of Missouri, have invented a certain new and useful Improvement in Revolving Ventilating-Fans, of which the following is a full, clear, and exact description, such as will enable others skilled in the art to which it appertains to make and use the same, reference being had to the accompanying drawings, forming part of this specification.

This invention relates to improvements in electrically operated rotary fans of the type wherein one or more fans with independent motors are arranged for revolution about a mounting or support for the purpose of distributing the fan's influence. The revolution of fans of this character has been obtained in different fashions, most commonly through the reaction of the fan blades upon the air. It is the principal purpose of my invention to provide a novel revolving fan construction wherein the revolution of the fan is obtained by a special form of driving mechanism which is actuated by one of the fan motors.

A further object of my invention is to provide a form of mechanism whereby this result is obtained, and wherein the fan together with its actuating motor is adjustable to different angles relative to the support about which it revolves.

A further object of my invention is to provide a mechanism which will secure the operative revolution of the fan at a speed which will be constantly in definite predetermined proportion to the speed of operation of the fan motor and which, by virtue of that fact, can be accurately controlled as to speed of operation.

A further object of my invention is to provide a fan construction wherein a plurality of fans are driven each by its individual motor, the motors being independently adjustable to different inclinations and all of the motors being revolved about a supporting member by power derived from one of the fan motors.

A still further object of my invention is to provide a construction which will secure a continuous and thorough lubrication of the operating parts upon the actuation of the revolving mechanism.

Another object is to improve generally

upon the construction of fans of this character with the purpose of providing a simple, strong, durable, economical and easily adjusted apparatus.

Other and further objects will be obvious or pointed out hereinafter.

In the accompanying drawings, I have shown for the purpose of illustration one form of my invention embodied in a ceiling fan, that is, a form in which the device is arranged to be supported from above, as from a ceiling. It is obvious, however, that the invention may also be embodied in a structure designed to be supported upon a column, or in other suitable fashions.

In the embodiment herein illustrated—

Figure 1 represents a side elevation of the device;

Fig. 2 a top or plan view;

Fig. 3 a vertical section substantially on line 3—3 of Fig. 2;

Fig. 4 a horizontal section substantially on line 4—4 of Fig. 1;

Fig. 5 a detail in section substantially on line 5—5 of Fig. 4;

Fig. 6 a detail illustrating the terminal connection arrangement;

Fig. 7 is a detail showing a fragmentary elevation of the revoluble frame member;

Fig. 8 is a detail showing a fragmentary side elevation of a motor arm.

Referring to the various parts by means of the reference numerals, it will be understood that 1 represents a supporting connection which may also form an outlet conduit for the electrical wiring. Supported thereon and secured thereto by suitable means 2, is a pedestal member 4. This pedestal member includes the socket portion 5, which engages the supporting member 1, the cover plate 6, which extends annularly from the socket member, the bearing portions 7 and 7' which form a sleeve-like member extending axially from the socket and cover plate members; and an annular toothed member 8 disposed intermediate and on the axis with bearing portions 7 and 7'. At the lower extremity of the pedestal member is supported a base member 9 into which the threaded lower end of the pedestal member 105 is screwed. The base member includes an annular upwardly extending flange 10 which forms a dish-like receptacle, within which is mounted a race ring 11. A casing portion 12 is also supported on the base member and 110

encompasses the lower portion of the flange 10. From the base member 9 depends a housing portion 14 having the inwardly presented brackets 15. A cover 16 closes the housing 14, and forms a support for an electrical switch 17.

On the pedestal member, intermediate the cover plate 6 and the base member 9, is rotatably mounted the frame member 18. This frame member is supported on ball bearings 19 which run on the race ring 11, and has axial engagement with the curved faces of the bearing portions 7 and 7'. Intermediate its areas of bearing upon bearing portions 7 and 7', the rotary frame member 18 takes the form of a gear housing with lateral annular flanges 20, and bosses 21 disposed concentrically with said flanges. Shaft housing portions 22 extend intermediate the flanges 20 and the bosses 21. Each of the annular flanges 20 has a circular lip 24 extending laterally.

Mounted on each of the annular flanges is a motor arm 25 terminating in a circular cover portion 26 which fits against the face of the annular flange 20 and has a circular journal flange 27 which bears internally against the inner face of the lip 24. Concentric with the flange 27 the cover portion 26 is formed with a boss 28, which boss, together with the opposite boss 21, is pierced for the reception of a pivot bolt 29. When the clamp nuts 30 are turned up on the end of pivot bolt 29, motor arm 25 will be held clamped against the face of the annular flange 20, with the circular flange 27 having internal bearing against the face of the lip 24. Inasmuch as the bolt 29 is concentric with the lip 24 and flange 27, the arm 25 may be swung about said bolt as an axis, so that the angularity of the arm relative to frame member 18 may be changed at will. The arm 25 may be retained at any of said angular adjustments desired by a suitable fastening means, such as the latch pin 31, which is mounted in a transversely extending sleeve 32 formed on the arm 25, and spring pressed toward flange 20. By virtue of the provision of suitable apertures or seats 34 in flange 20, latch pin 31 is adapted to engage the flange to hold the arm 25 against movement thereon. The motor arms 25 support at their outer extremities the motors 23, whose rotors support the fans 33 in the customary fashion. From the rotors of one of these motors extends a shaft 34 which extends alongside of the arm 25 and has bearings thereon at 35 and 36. A screw plug 37 cooperates with the shaft 34 and the bearing 35 so that a stuffing box may be provided to retain lubricant within the housing portion 26. Within said housing portion and intermediate the bearings 35 and 36, shaft 34 carries a worm 38 which is keyed thereto for rotation therewith. Upon the

adjacent pivot bolt 29 is revolvably mounted a sleeve 39 which carries at one end a worm pinion 40 meshing with the worm 38, and at its other extremity a worm 41. This worm 41 meshes with the fixed pinion or circumferential rack 3 which is mounted on the pedestal member 4.

By virtue of this arrangement, when shaft 34 is rotated by operation of the motor, worm 38 will be operated to turn sleeve 39 and worm 41 through the medium of worm wheel 40, and the rotation of worm 41 in engagement with fixed pinion 3 will cause rotary frame member 18, together with the parts carried thereby, to rotate about pedestal member 4. The arrangement thus provides a positive driving gear between the motor and the stationary support, the operation of which will cause the rotation of the frame member at a speed which is always in a constant proportion to the speed of operation of the motor. Consequently, the speed of revolution of the fans about the support can be directly controlled through the speed of the motor.

Upon the rotary frame member 18 are mounted casing portions 42 extending from the cover plate 6 to the flange 12, and inclosing the parts of the mechanism therebetween. These casing portions fit together in complementary fashion, and at their meeting edges are slotted to permit the passage of the motor arms 25 and the wires 44. These casing portions are secured to the rotary frame member 18 at their upper portions by means of screws 45, and adjacent their lower portions are secured thereto by radially extending screws 46. Tangentially arranged screws 47 secure the casing portions to each other at their lines of contact. The length of the slots in the casing portions 42 is sufficient to accommodate a considerable vertical movement of arms 25, so that the latter may be adjusted to different angles vertically. In the case of the arm carrying the shaft 34, this adjustment is permitted by virtue of the movability of the rotary frame member relative to the fixed pinion 3 so as to accommodate any desired position of worm 38 relative to the axis of pinion 40.

As a means for keeping the working parts thoroughly lubricated, the rotary frame member 18 is provided with a spiral groove 48 which extends from the lower extremity of the frame member within the annular flange 10 up to the gear housing portion of the frame, and thence up to a chamber 49 which is formed in the upper portion of frame member 18. When suitable lubricant is disposed within the cup formed by the flange 10, and mechanism is actuated to rotate frame 18 around pedestal member 4, the lubricant will feed up through the spiral groove 48 into the gear housing portion of

the frame and thence up to the chamber 49. When the mechanism is at rest the lubricant will feed downwardly through the spiral groove from the chamber 49. Inasmuch as the contact of the housing portions 26 upon the annular flanges 20 forms a completely inclosed chamber about the gearing, all working parts will be subjected to thorough lubrication without opportunity for the escape of the lubricant.

The current is supplied to the motors 31 in any suitable fashion. That shown comprises the slip rings 50 suitably insulated and mounted on the upper portion of the rotary frame member, and brushes 51 arranged to coöperate therewith and mounted in the cover plate 6. From the collector rings 50, the wires 44 lead down to the arms 25, and out through the casing portions 42 to the motors.

In the shaft 34 is arranged a suitable escapement clutch 52 of any suitable form such as will permit the shaft being uncoupled at will to disconnect the revolving mechanism from the motor, and such as will be operable by excessive pressure to permit escapement in case the revolving portions should meet with an obstruction. Or a suitable clutch 43 may be placed in sleeve 39.

By virtue of the mechanism above described, it will be observed that the revolute movement of the fans is derived positively from the fan motor, and may be regulated as to speed by regulation of the speed of the fan motor. Furthermore, it is to be observed that the fans are adjustable independently to various angles, without affecting in any fashion the operation of the rotating mechanism. A neat, compact and substantially dust-proof mechanism is provided, and thorough lubrication of the working parts is secured. Suitable mounting for the switch 17 and the speed controlling coil 54 is provided. The latch pins 31 are operable from the exterior of the casing, so that no dismantling of the device is required in order to adjust the fans.

I am aware that my invention is susceptible of changes, modifications, and adaptations not herein specifically described or shown, but comprehended nevertheless within the scope and spirit of my invention as indicated in the following claims.

What I claim is:

1. In a revolving fan mechanism, the combination of a supporting pedestal, a frame member rotatably supported thereon, laterally projecting arms each having independently adjustable connection with said frame member, an independently operable motor supported by each arm, a fan operably supported by each motor, means driven by one of said motors for rotating said frame member about said pedestal, and an independently operable means coöoperating

with each of said arms for securing it in selectively different positions relative to said frame member.

2. In a revolving fan mechanism, the combination of a pedestal member including 70 upper and lower annular flange portions, a bearing portion disposed intermediate said flange portions, a frame member rotatably mounted on said bearing portion, laterally extending arms mounted on said frame 75 member, fan motors mounted at the outer extremities of said arms, and an annular casing portion supported on said frame member and extending intermediate the flange portions and coöperating therewith 80 to inclose the frame member.

3. In a revolving fan mechanism, the combination of a supporting pedestal, a frame rotatably mounted thereon, independently adjustable arms carried by said frame, 85 independently operating motors supported on the arms, means actuated by one of said motors and coöperating with the pedestal to rotate the frame and cause the revolution of the motors about the pedestal, and fans 90 operably associated with the motors.

4. In a mechanism of the class described, a pedestal member, an upwardly extending annular flange supported thereon to form a cup-like receptacle, a frame member rotatably mounted on said pedestal and having its lower extremity extending within said receptacle, a portion of said frame member being shaped to form a gear housing, gearing mounted therein and operably associated 100 with a portion of the pedestal, the face of said frame member having bearing on said pedestal being provided with a spiral groove extending intermediate said housing and the lower extremity of said frame member, and 105 means for actuating the gearing to rotate the frame member on the pedestal.

5. In a mechanism of the class described, a pedestal member, a cup-like receptacle supported at its lower extremity, a frame 110 member mounted on said pedestal and having a gear housing formed therein above its lower extremity and a chamber formed therein above the gear housing, the lower extremity of the frame member extending 115 within the receptacle, and the portions of the frame member having bearing engagement on the pedestal being formed with a spiral groove leading from the lower extremity of the frame member to the gear 120 housing and from the gear housing to the said chamber, all for the purpose described.

6. In a mechanism of the class described, a supporting pedestal, a frame mounted thereon for rotation thereabout, a fan actuating motor adjustably supported on the rotatable frame so that the inclination of the fan's axis may be varied, a shaft actuated by and adjustable with the fan motor, and a transmission shaft journaled on the frame 130

- and carrying means having intermeshing engagement with portions on the pedestal and the first mentioned shaft whereby the frame is rotated by operation of the motor.
- 3 7. A revolving fan mechanism including the combination of a stationary pedestal member, a frame member mounted for rotation thereon, arms supported by and extending laterally from said frame member, fans and fan motors carried at the extremities of said arms, and independently operable means associated with the respective arms for securing said arms selectively at different inclinations relative to the pedestal.
- 10 8. A revolving fan mechanism including a pedestal member, a frame member rotatably mounted thereon, motor arms pivotally connected to said frame member for support-

ing motors at the outer ends thereof, motors at the outer ends of said arms, means for adjusting said motor arms and motors with respect to said frame member, a gear supporting shaft coaxial with the pivotal point of one of said arms, a worm and gear connection between the armature shaft of said motor and said gear supporting shaft, and a worm and gear connection between said gear supporting shaft and said pedestal.

In testimony whereof I hereunto affix my signature in the presence of two witnesses, so this 10th day of July, 1916.

HERBERT I. FINCH.
